L. M. LEIBOWITZ.

COLLAPSIBLE CRATE.

APPLICATION FILED JULY 12, 1909. RENEWED APR. 15, 1910.

958,749.

Patented May 24, 1910.

UNITED STATES PATENT OFFICE.

LEON M. LEIBOWITZ, OF NEW YORK, N. Y.

COLLAPSIBLE CRATE.

958,749.

Specification of Letters Patent. Patented May 24, 1910.

Application filed July 12, 1909, Serial No. 507,272. Renewed April 15, 1910. Serial No. 555,715.

To all whom it may concern:

Be it known that I, LEON M. LEIBOWITZ, a citizen of the United States, residing at New York, in the county of New York and 5 State of New York, have invented certain new and useful Improvements in Collapsible Crates, of which the following is a specification.

This invention relates to collapsible crates 10 or boxes preferably made of wood, and has especial reference to a device of this character, which is simple of construction, easy to operate, and one which is positively locked in either normal or collapsed position, the 15 same locking means being employed for both positions.

For a full understanding of the invention reference is to be had to the following detail description and the accompanying drawings, in which—

Figure 1 is a perspective view of a crate in normal position; Fig. 2 is a plan view of the same crate collapsed; Fig. 3 is a horizontal sectional view substantially on the 25 line 3—3 of Fig. 4; Fig. 4 is a transverse vertical section on the line 4—4 of Fig. 3; Figs. 5 and 6 are sectional details substantially on the lines 5—5 and 6—6, respectively, of Fig. 4; Fig. 7 is a modified form 30 of lock spring hereinafter described; Fig. 8 is a face view of a thimble employed in connection with the lock, and Fig. 9 is a similar view of the plate in which said thimble is mounted for rotation.

Throughout the following description and on the several figures of the drawings similar parts are referred to by like reference characters.

A crate constructed in accordance with 40 this invention comprises preferably end members 10 and 11, a central partition 12, side members 13 and 14, a bottom 15, and a top 16. The side members 13 and 14 are hinged to the ends of the end members and 45 central partition in such a manner as to always remain parallel to each other in all positions of the crate.

Any convenient number of pairs of hinges 17 may be employed for connecting the above 50 parts, it being understood that while only one hinge is shown at each joint, two or more may be employed if desired, and the hinges may be of any suitable construction.

By referring to Figs. 2 and 3 the folding 55 operation may be understood. The members 10 and 12 are adapted to swing in the direc-

tion of the dotted arcs and lie substantially against the inner face of the side wall 13. The member 11 swings also in the same direction and is extended beyond the end of 60 said side wall 13. Similarly the wall 14 at the same time will be brought into position to be engaged by the members 11 and 12.

The crate is held in its normal or open position by a peculiar locking means co-operating with the top and bottom members and the end members. The top 16 is connected by a pair of hinges 18 to the side wall 14, and when in normal position said top rests upon the upper edges of the side and end 70 members. The bottom 15 is substantially a counterpart of the top, and is connected by hinges 19 to the side wall 13 preferably to that edge of the crate diagonally opposite the hinges 18 so that the top and bottom 75 members swing in opposite directions. Each of said top and bottom members swings through an angle of 270 degrees against the side member to which it is hinged during the collapsing operation. 80

The locking means above referred to comprises sets of bolts 20, each of which passes through the end edge of the top or bottom, as the case may be, and into a hole or socket 21 in the end member adjacent thereto. The 85 bolt 20 is provided with a beveled face 22 and one or more notches 23. The end member is provided on its inner wall, just opposite the socket 21, with a catch 24 connected to a spring 25 whereby the catch 24 will be 90 caused to engage any one or more of said notches 23. When the crate is in the position indicated in Fig. 1 the bolts will be passed through the top and bottom members as above stated and their inner ends will be 95 locked in the several sockets 21, substantially in the manner indicated in Fig. 6. The ends of the members 15 and 16 are preferably reinforced by sheet metal straps 26, through 100 which the bolts pass. The beveled ends 21 of the bolts when the latter are inserted push the catches 24 inwardly against the tension of the springs 25 so that no special means may be required to cause the bolts to become locked. Each of the bolts 20 is provided 105 with a hook 20' which extends inwardly toward the center of the crate and thence downwardly through the top or bottom member with which it is used. The point 20'' of the hook extends preferably through 110 said top or bottom member. By this construction of the hook the operator always

knows which is the side of the bolt that will coöperate with the catch, and also the point of the hook provides a better interlocking between the bolt and the crate when in normal position.

In order to release the bolt, the spring 25 is adapted to be pushed inwardly to withdraw the catch 24 from the bolt, by means of a pin carried by the operator and inserted 10 into a hole 27 bored transversely through the end member. The said pin or tool may be engaged directly against spring 25, or the latter may be provided with a stud 28 which normally projects into the hole 27, and hence 15 insuring proper coöperation between the spring and the bolt.

When the crate is in collapsed position the same bolts coöperate with the several parts to maintain the same in said position. The 20 bolts in this position coöperate in the several sockets and with the catches 24 substantially the same as in the first mentioned, although the bolts may enter the sockets 21 to a greater extent so that the points 20" of the 25 hooks will engage over the edges of the parts folded against the end members. The bolts are released from this position in the same manner as above set forth.

As indicated in Figs. 5, 8, and 9 a plug 28^a 30 may be introduced into the hole 27, said plug being provided with a key-slot 28'. Also a plate 29 may be secured to the outer wall of the end member and having a thimble 30 provided with a key-slot 30' of 35 the same configuration as the slot 28'. The thimble is mounted in the plate 29 for rotation and when a key is introduced into the thimble the latter must be rotated so as to

bring the two slots into alinement in order that the key may pass through and depress 40 the stud 28.

As indicated in Fig. 7 the spring 25' may be double ended having catches 24 at both ends. In this instance a plurality of bolts 20 would be provided for coöperation with 45 one spring. That is to say, there may be four bolts instead of two employed in connection with either the top or bottom of the crate.

Having thus set forth the preferred embodiment of the invention, what is claimed as new is:—

The herein-described collapsible crate comprising a pair of end members having sockets in their upper and lower edges, a 55 pair of side members hinged to the end members and foldable against the inner faces thereof, respectively, top and bottom members hinged to the side members and foldable thereagainst, said top and bottom 60 members having holes in alinement with said sockets when the crate is in normal position, and sets of detachable locking bolts adapted to pass through said holes into said sockets to lock the crate in open position, 65 said bolts being adapted to be seated in the same said sockets when the crate is folded and having hooked outer ends spanning the outer edges of the top, bottom, and side members, as specified.

In testimony whereof I affix my signature in presence of two witnesses.

LEON M. LEIBOWITZ.
